US00D946119S

(12) **United States Design Patent** (10) **Patent No.:** **US D946,119 S**
(45) **Date of Patent:** **** Mar. 15, 2022**

(54) **FAUCET**

(71) Applicant: **KRAUS USA PLUMBING LLC**, Port Washington, NY (US)

(72) Inventor: **Russell Levi**, Port Washington, NY (US)

(73) Assignee: **KRAUS USA PLUMBING LLC**, Port Washington, NY (US)

(**) Term: **15 Years**

(21) Appl. No.: **29/764,279**

(22) Filed: **Dec. 29, 2020**

(Continued)

FIG. 1 is a front perspective view of a faucet in accordance with the present design;

FIG. 2 is a front elevational view thereof;

FIG. 3 is a rear elevational view thereof;

FIG. 4 is a right side elevational thereof;

FIG. 5 is a left side elevational view thereof;

FIG. 6 is a top plan view thereof;

FIG. 7 is a perspective view of the faucet shown with a sprayer of the faucet in a pulled down configuration;

FIG. 8 is a front perspective view of a another embodiment of a faucet in accordance with the present design;

FIG. 9 is a front elevational view thereof;

FIG. 10 is a rear elevational view thereof;

FIG. 11 is a right side elevational thereof;

FIG. 12 is a left side elevational view thereof;

FIG. 13 is a top plan view thereof; and,

FIG. 14 is a perspective view of the faucet shown with a sprayer of the faucet in a pulled down configuration.

The broken lines shown are included for the purpose of illustrating a portion of the faucet that form no part of the claimed design.

1 Claim, 14 Drawing Sheets
